TOP STOP FOR SLIDE FASTENERS

Maurice Voity, Long Island City, N. Y., assignor to
 Universal Slide Fastener Co. Inc., New York,
 N. Y., a corporation of New York

Application September 16, 1940, Serial No. 356,898

5 Claims. (Cl. 24—205)

The present invention relates to slide fasteners, and more particularly to an improved form of top stop for the slider member, to be attached to a pair of cooperating element-holding tapes or stringers.

Heretofore, it has been found that the slider member tends to become jammed at the end of its closure movement, thereby preventing the slide fastener from being operable for reverse or opening movement and causing damage to the assembly. This has been partly due to the fact that the uppermost fastener elements on the opposed tapes are not properly spaced from each other. The jamming has also been partly due to the twisting of the tapes adjacent the uppermost fastener elements, causing misalignment of these elements.

Further, considerable difficulty has been encountered in providing a slide fastener assembly applicable as a closure for slits in garments, handbags, wallets or the like, wherein by virtue of the irregular contour of the garment incorporating the slit when worn, lateral twisting of the stringer and longitudinal displacement of one of the scoop element series with respect to the other is developed, causing misalignment of the scoops in relation to the slider being reciprocated, and consequent jamming of such scoops as the slider is displaced, all of which results in an unsightly appearance of the garment, handbag, wallet or the like in the zone of the slit closure.

It is one of the objects of the present invention to prevent this jamming by providing a top stop that will properly space the uppermost fastener elements on the opposed tapes and that will also prevent the portion of the tapes adjacent said uppermost fastener elements from twisting.

Top stops prior to the present invention have been secured to the tapes by merely gripping the beads thereof, some top stops having sharp edges embedded in opposite sides of the beads; others having their channel walls compressed on the beads in frictional engagement. The former of such stops has the disadvantage of eventually cutting through the bead, while with the latter type a strong pull on the tapes oftentimes pulls the bead out of the channel.

Therefore, the present invention has as another of its objects the provision of a top stop which will positively grip the beads of the tapes without injuring the beads and which will securely lock the beads within the top stops. Furthermore, to insure a powerful gripping of the tapes, the present invention provides a top stop

which not only grips the beads of the tapes, but also grips the tapes directly.

Another object of the present invention is to provide a top stop which is shaped to substantially conform with the top bridge or neck of the slider member.

A further object of the present invention is to provide a top stop of the character indicated which is inexpensive to manufacture, simple in construction, easily applied to the fastener tapes, compact, ornamental in appearance, and efficient and durable in use.

Other and further objects and advantages of the present invention will become apparent from the following description and the drawing referred to therein, in which:

Figure 1 is a top plan view of the end portion of a slide fastener assembly illustrating the slide member in its closed position adjacent a top stop embodying the present invention.

Figure 2 is a similar view after the slide member has been moved away from the top stop.

Figure 3 is an enlarged perspective view of the top stop.

Figure 4 is a sectional view along the line 4—4 of Figure 2.

Figure 5 is a plan view of a metal strip from which the top stop is manufactured.

Figure 6 is a similar view of the same metal strip in a later stage of manufacture.

Referring now to the drawing and particularly to Figures 1 and 2, I have illustrated a top stop embodying the present invention in association with a conventional slide fastener having interlocking fastener elements 10 arranged on the beads 11 of tapes 12 to form flexible stringers. The tapes 12 are adapted to be attached to the sides of the material adjacent the opening to be closed by the slide fastener. A slide member 13 is moved along the fastener elements 10 to open and close the fastener. A flap 14 is linked to a projection 14' of slide member 13. Slide member 13 has an interior channel 15 connected with a pair of diverging outlets 16 at the top of the slide member, the outlets 16 being laterally spaced by a neck 17. The top of the slide member 13 is formed roughly in the shape of an inverted V with neck 17 at the apex thereof.

The top stop 18, embodying the present invention, is arranged at the end of the opening defined by the cooperating stringers normally fastened at the bottom, so as to stop the slider at the end of its closing movement to seal and form a closure for the slit of the garment in which it is applied.

The top stop 18 may be formed from a strip of metal 19 (Fig. 5), such as of brass. It is to be understood, of course, that other metals and other materials, for example, plastics, may be employed. For each top stop to be formed from the strip 19, four holes or openings are punched therein. The diameter of each of these holes is preferably slightly less than the diameter of the beads 11 which are arranged on tapes 12.

Two of the holes 20 and 21 are made relatively close to each other, being separated by a narrow bridge 22. The remaining holes 23 and 24 are separated a relatively greater distance from holes 20 and 21, being arranged a substantial and equal distance from the bridge 22 on opposite sides thereof. Holes 23 and 20 are then connected together by a slot 25; and holes 21 and 24, by a slot 26. The slots are substantially narrower than the thickness of the tapes 12. Shoulders 27 are thereby formed at each hole. The slots 25 and 26 are then expanded (as illustrated in Fig. 6) so as to be wider than the thickness of the tapes 12, causing the holes to spread and also so as to have a greater diameter than the beads 11. The strip 19 is then sheared along the lines 28-28 (Fig. 6) so as to produce a cut-out blank from which top stop 13 is formed. By similar operations additional blanks are obtained from the strip 19.

The cut-out blank is formed into the shape illustrated in Fig. 3 by bending the central portion thereof to form an arc and then further bending the end portions until the ends 29 and 30 face inwardly, substantially resulting in a discontinuous ellipse. One of the end portions 35 includes hole 23 and a minor fraction of slit 25, the other end portion including hole 24 and a minor fraction of slit 26. The distance between the ends 29 and 30 is slightly greater than the width of the neck 17 of the slide member 13. The distance between holes 23 and 24 is greater than the distance between the inner walls defining the diverging outlets 16, but less than the distance between the outer walls defining 40 said outlets 16. The top-stops may be suitably metal plated.

The top stop 18 is secured to the tapes 12 adjacent the topmost of the fastener elements 10 by arranging one of the beads 11 to pass through holes 21 and 24, and by arranging the other of the beads 11 to pass through holes 20 and 23. (See Fig. 4.) A part of each of the tapes 12 is arranged within the slots. The sides of the top stop 13 are then squeezed together so as to close the holes around the beads, thereby gripping the beads, and the slots are narrowed so as to grip the parts of the tape within said slots.

Shoulders 27 prevent the beads from slipping out of the holes and the pressure of the top stop on the bead and the direct pressure on the tapes cause the top stop to grip the tapes firmly. Moreover, since the top stop grips a portion of each of the tapes within the slots, and since it is flat, it tends to keep the portions of the tapes thereadjacent flat and in alignment with each other. Twisting of the tape near the topmost of the fastener elements, with consequent mis-aligning of these elements and jamming of the slide member is therefore prevented. Furthermore, it will be seen that the beads are properly spaced apart by the top stop so that the uppermost fastener elements readily enter and leave diverging outlets 16, thereby further preventing jamming of the slide member 13. The beads 11, 11 are spaced apart above the top

stop at a distance equal to the width of the bridge 22 of the top stop.

It is preferable that strip 19 of the top stop be made as wide as the width of the fastener elements. Thus, the top stop will be flat and on the same plane as the fastener elements when it is secured to the tapes, and will, therefore, not be likely to accidentally catch onto anything. As seen in Figure 1, when slide member 13 is drawn into closed position, neck 17 of slide member 13 passes between the ends 29 and 30 of the top stop. The projecting ends are thus covered.

While I have illustrated and described details of a preferred embodiment of my invention, I do not intend to be limited thereby, the scope of the present invention being defined by the following claims.

I claim:

1. A top stop for a slide fastener assembly including opposing stringer tapes with beads along the edges thereof on opposite sides of a slit defined thereby, said top stop having an arcuate central portion with two spaced openings therein, integral end portions extending towards each other from said central portion, said end portions each having an opening connected by a slot to the adjacent opening in the central portion, said connected openings being adapted to spacedly receive therein the beads of the respective stringer tapes and the interconnecting slots being adapted to receive a body portion of the respective tapes.

2. A top stop for a slide fastener assembly including opposing stringer tapes with beads along the edges thereof on opposite sides of a slit defined thereby, said top stop having an arcuate central portion with two spaced openings therein, integral end portions extending towards each other from said central portion, said end portions each having an opening connected by a slot to the adjacent opening in the central portion, the respective spaced openings in the central portion being closer to one another than the respective openings of the end portions, said connected openings being adapted to spacedly receive therein the beads of the respective stringer tapes and the interconnecting slots being adapted to receive a body portion of the respective strips.

3. A top stop for a slide fastener assembly including opposing stringer tapes with beads along the edges thereof on opposite sides of a slit defined thereby, said top stop having an arcuate central portion with two spaced openings therein, integral end portions extending towards each other from said central portion, said end portions each having an opening connected by a slot to the adjacent opening in the central portion, the slots being narrower than the openings connected thereby, said connected openings being adapted to spacedly receive therein the beads of the respective stringer tapes and the interconnecting slots being adapted to receive a body portion of the respective strips.

4. A top stop for a slide fastener assembly including opposing stringer tapes having beads along the edges thereof and a plurality of interlocking fastener elements arranged along the beads to define opposite sides of a slit, and a slide member adapted to be moved along the fastener elements to lock and unlock the elements and having spaced diverging outlets at the top thereof, said top stop having an arcuate central portion with two spaced openings therein, integral end portions extending towards each other from said

central portion, said end portions each having an opening connected by a slot to the adjacent opening in the central portion, each pair of connected openings being adapted to spacedly receive the bead of one of the stringer tapes and the interconnecting slots being adapted to receive the material adjacent the bead, said openings in the central portion being spaced apart a distance less than the openings in the end portions and said openings in the end portions being spaced apart a distance sufficient to align the opposing heads received therein with the diverging outlets of the slide member.

5. A top stop for a slide fastener assembly including opposing stringer tapes having beads along the edges thereof and a plurality of interlocking fastener elements arranged along the beads to define opposite sides of a slit, and a slide member adapted to be moved along the fastener elements to lock and unlock the elements and

10 15 20

having a neck defining spaced diverging outlets at the top thereof, said top stop having an arcuate central portion with two spaced openings therein, integral end portions extending towards each other from said central portion, said end portions each having an opening connected by a slot to the adjacent opening in the central portion, each pair of connected openings being adapted to spacedly receive and clamp the bead of one of the stringer tapes and the interconnecting slots being adapted to receive and clamp the material adjacent the bead, said end portions at their free extremities being spaced apart a distance greater than the width of the neck of the slide member to accommodate said neck therebetween, said openings in the end portions being spaced apart a distance sufficient to align the spacedly clamped beads with the diverging outlets of the slide member.

MAURICE VOITY.
